UNITED STATES PATENT OFFICE.

WILLIAM DAVID STERNBERG, OF LONDON, ENGLAND.

HEEL.

Application filed June 8, 1923. Serial No. 644,234.

To all whom it may concern:

Be it known that I, WILLIAM DAVID STERNBERG, a citizen of the United States of America, and residing at 19 City Road, London, E. C. 1, England, have invented certain new and useful Improvements in Heels, of which the following is a specification.

This invention relates to heels for boots or shoes, of the type comprising a substantially D-shaped carrier and a detachable wearing piece of horseshoe or like shape.

The object of the invention is to provide an improved heel of the above kind, the wearing piece of which may be readily detached and replaced by a new piece, the arrangement being such that when in position the wearing piece is firmly secured against accidental displacement.

According to the invention the wearing piece is provided with a core element adapted to cause the piece to be secured in relation to the carrier.

Further features of the invention will be hereinafter described and defined in the claims.

The present invention will now be described with reference to the accompanying drawings in which—

Figure 1 is an inverse plan view of one form of the attachment shown applied to the heel of a boot or shoe;

Figure 2 is a sectional view thereof taken on the line 2—2, Figure 1;

Figure 3 is a front end view of the same;

Figures 4, 5 and 6 are a plan view, elevation and plan view respectively of the parts from which the wearing piece is formed.

Figure 7 is a plan view of a modification;

Figures 8 and 9 are a plan view and sectional elevation of a further modification;

Fig. 10 is a sectional elevation taken on line 10—10 of Fig. 7, and

Figure 11 is an inverted plan of a further modification.

Like reference characters represent similar points throughout the figures of the drawings.

The attachment comprises a carrier member or block *a* of D shape of vulcanite, leather, rubber or any other suitable material and a wearing member of substantially horseshoe shape *b*, which may also be of leather, vulcanite, rubber or other

suitable material. The carrier, member or block *a*, is of the same general shape as the heel, but is narrower and shorter in length so that when the carrier is placed in position with its inner edge in alignment with the inner edge of the heel of the boot, a space or gallery is left around the side and edge of the carrier to receive the wearing member. The carrier is secured in the position above indicated in any suitable manner to the heel *c*, as for example, by nailing or screwing, and when secured thereto is intended to remain more or less permanently in position.

The side and outer end edges of the carrier are undercut or bevelled as shown at *d*, for a purpose which will hereafter appear.

Around the carrier, a wearing piece *b* of substantially horseshoe shape is adapted to be fitted. The wearing piece is provided with bevelled or inclined inner edges as shown at *f*, corresponding with the bevelled or undercut edges *d* on the carrier.

The wearing pieces may be conveniently formed from a straight strip or length of material *g* of the cross-section shown, having a channel, groove or passage extending longitudinally or throughout its length into which is inserted a member or core *h*, so that when in place in the wearing member the latter is bent into its correct shape. The member or core is preferably of resilient material, for example, resilient metal, so as to act as a spring to tend to maintain the bevelled portions of the wearing member and carrier in close engagement, and facilitate the placing of the former on the latter.

Co-operating means are provided on the wearing member and carrier to prevent the wearing member from creeping or sliding off the carrier and this may be effected by making the core member of a length of material such that when placed in the channel or groove, portions are left that are bent over substantially at right-angles as shown at *i*, such bent portions being adapted to engage recesses or depressions *j*, in the carrier member. In the form shown in Figures 1, 2 and 3, the ends of the wearing member are provided or formed with slots or recesses *j*, that extend inwardly from the inner edge of the wearing member to the channel therein and after the core or retaining member

has been inserted in the channel the ends of the core are bent over laterally as shown so as to leave portions to engage the recesses i' on the edges of the carrier member.

5 In the form shown in Figs. 7 and 10 a reinforcing plate o embedded in the carrier member is provided extended to engage recesses o' in the wearing member, the plate being so arranged that in fastening down 10 the carrier the plate is drawn towards the heel.

In the form of the invention shown in Figs. 7 and 10, a modification of the means above mentioned is illustrated. In this 15 form, in addition to bending the core member at its ends i to engage depressions or recesses in the carrier member, the ends of the wearing member itself are each provided on their inner faces with a protuberance or 20 projection as shown at r , that is adapted to enter a corresponding recess l in the edge of the carrier member. In this form the engaging surfaces of the bevelled edges of the carrier and wearing member may also 25 be ribbed or corrugated as shown at m , in order to more effectively prevent loosening or creepage of the wearing member.

Referring now to Figures 8 and 9, there is 30 shown therein a form of wearing member in which the channel, groove or recess is located at the lower end of the recess or slit n , extending upwardly to the upper surface thereof. This provides a form in which the core may be more readily inserted in the 35 channel, as by spreading it open at one end, inserting one end of the core and then pressing the remaining portion of the core into the recess. The ends of the core may then 40 be bent over as shown at i , through apertures extending from the channel to the bevelled edge, or such end can be bent over before placing the core in the channel or groove. This slit n is also used with the forms shown 45 in Figs. 1, 2, 3, 7 and 10, but the slit is not illustrated in Figs. 1 and 7, to avoid the liability of confusion being caused by too many dotted lines.

In the modification shown in Figure 11 50 I have shown a further embodiment of the means for retaining the wearing piece in place in which projections or protuberances at the ends of the wearing piece engage cut away portions or angular recesses in the carrier.

55 In all the modifications described the wearing members may be conveniently formed from a length of material g of the cross-section shown by cutting said length into sections of suitable dimensions to form the individual wearing pieces. This is particularly advantageous in the case where the wearing pieces are to be formed of rubber as long lengths which may be moulded and then cut into sections of the correct length. 60 This provides a construction in which the

carrier has portions or surfaces of increased width at the parts where greater wear is likely to take place.

It is usually found that the outer side of the rear part of a heel is subjected to most 70 wear, and consequently becomes worn down, while the remainder of the heel is comparatively little worn.

It will be seen that when said portions have become worn the wearing pieces may 75 be changed from one heel to the other so that the unworn portions will take up the outer position in which most wear will take place.

By this transfer method the wearing 80 pieces may be worn down substantially uniformly, consequently increasing the life thereof to a considerable extent.

The carrier in the foregoing specification has been described as an attachment for a 85 heel after the boot or shoe has been manufactured, the carrier, however, may be formed during manufacture as an integral part of the heel of the boot or shoe and shipped from the factory with an appropriate 90 wearing piece of any of the forms described mounted thereon together with a series or set of spare wearing pieces for application in place of the original one supplied when the latter is worn. In this case 95 the carrier may be nailed, sewn or otherwise secured in position as an integral part of the remainder of the heel.

Having now described my invention what I claim as new and desire to secure by Letters Patent is:—

1. A heel for boots and shoes including a carrier element, a wearing member of substantially horse-shoe shape extending around the sides and the outer end of said carrier element, the carrier element being recessed, a resilient horse-shoe shaped core member embedded in said wearing member, and lugs at the ends of one of said members extending 105 into the carrier element recesses, said core and lugs detachably locking the wearing member and the carrier element together.

2. A heel as claimed in claim 1 in which the wearing member is split longitudinally from one of its surfaces to facilitate the positioning of the core in the wearing member.

3. A heel as claimed in claim 1 in which the carrier element and wearing member are provided with contacting corrugated surfaces to prevent creeping of the wearing member on the carrier element.

4. A heel as claimed in claim 1 in which a metal plate is arranged in the carrier element and has a projecting edge extending into the wearing member.

5. A heel for boots and shoes including a carrier element of substantially D-shape arranged at the lower end of the heel and 125 provided with beveled side and rear sur-

faces, a wearing member of substantially horse-shoe shape extending around the side and rear edges of the carrier element and provided with an inner beveled surface engaging the beveled surfaces of the carrier element, said carrier element having recesses at the opposite sides of its front end, and a substantially U-shaped resilient metal core

member embedded in the wearing member and having inwardly extending lugs at its ends engaging the recesses of the carrier element for locking the wearing member in position.

In testimony whereof I have signed my name to this specification.

WILLIAM DAVID STERNBERG.
